UNITED STATES PATENT OFFICE

2,328,535

COVER STRUCTURE FOR STORAGE BATTERIES

Cornelius Ambruster, Roslyn, Pa., assignor to The Electric Storage Battery Company, Philadelphia, Pa., a corporation of New Jersey

Application June 26, 1940, Serial No. 342,435

9 Claims. (Cl. 136—170)

Objects of the present invention are to provide the jar or container with flat inside and outside walls so that its cost is reduced, to provide for properly positioning an inside cover having a downward and outward peripheral flange so that the sealing compound arranged in the channel provided by the flange and the flat inside face of the jar wall may be properly applied and retained in place, to oppose disturbance of the sealing compound in the event of upward growth of the element or elements and generally to improve the cover construction of a storage battery cell.

Other objects of the invention will appear from the following description at the end of which the invention will be claimed.

Generally stated the invention consists in spaced supports projecting from and beyond the rim of the cover and resting on the top of the jar wall and having angularly disposed feet engaging the outside face of the jar wall, with or without tongue and groove elements interposed between the supports and the cover and the feet and the jar wall; the cover being provided with an opening larger than the terminal post which passes through it, with or without spray-deflecting elements on the post and cover.

The invention also consists in the improvements to be presently described and finally claimed.

In the following description reference will be made to the accompanying drawing forming part thereof and in which,

Figure 1 is an elevational view principally in section illustrating a cover structure embodying features of the invention.

Figure 2 is a partial top or plan view of the same.

Figure 3 is a sectional view illustrating a detail of construction useful in shipping; and

Figure 4 is a perspective view of one of the supports.

In the drawing, *a* indicates the element or plate structure provided with a terminal post *b* and supported on ribs *c* at the bottom of the battery jar. *d* indicates a cover downwardly and outwardly flanged at its periphery as indicated at *e* and the cover fits inside of the jar or container generally indicated at *f*. There is nothing new about the construction as above indicated, and I will now proceed to describe the present invention. The inner face *1* and the outer face *2* of the side wall of the jar are flat. They may, therefore, be produced at comparatively little cost. The hole or opening *3* in the cover is larg-

er than the terminal post *b* which extends through it and the portion of the cover surrounding the opening *3* is dished downwardly as at *4*. *5* is a support provided with a foot *6*. A number of these supports *5* in spaced relation are attached to the cover *d* so as to project beyond its edge and to rest on the top of the side wall of the jar. The feet *6* of the supports *5* engage the outside face of the jar wall and hold it and the cover in fixed relation. The channel *g* receives sealing compound shown at the right, Fig. 1, and which is not shown at the left for the sake of clearness, and the sealing compound is introduced into the space or channel *g* in the usual way and since the supports *5* are spaced they do not interfere with its introduction. As shown the supports *5* are attached to the cover by rivets *7* and they are arranged in recesses are grooves provided in pads *8* on the cover. The feet *6* are shown arranged as tongues in grooves *9* provided in the outer face of the jar wall, thus avoiding any substantial increase in the outside dimension of the cell. The supports *5* may be made of lead alloy or other suitable material and they may be made integral with the cover or attached thereto. *10* is an upstanding rib on the cover and it surrounds the opening *3*. *11* is a canopy shown as mounted on the terminal post *b* and it is provided with a drip skirt *12*.

30 In use growth or movement in upward direction of the element *a* is without effect upon the cover and has no tendency to disturb the sealing compound because the terminal post passes through an opening in the cover larger than the post itself. Since the cover *d* and jar are held against relative movement by the supports *5* and their feet *6*, tendency to disturb the sealing compound is opposed. It is an advantage that there are no capillary channels between the post and the cover through which electrolyte might creep and attack the terminal post. The canopy *11* with its drip skirt and the rib *10* serve to return liquid that may have escaped, for example as spray through the space *3*, back into the cell.

40 In shipping use may be made of a tapered stopper *13* and washer *14*, Figure 3, in order to steady the element *a* by engaging the terminal post *b*, pressure being exerted on the stopper *13* by means of the threaded portion of the post *b* and canopy *11*. In use, however, these elements *13* and *14* are removable as indicated in Figure 1. The elements *13* and *14* also serve to prevent electrolyte from splashing out of the jar during shipment.

55 Matter shown and described but not claimed

herein is claimed in my divisional application Ser. No. 411,669, filed September 20, 1941, for Vent structures for storage batteries.

It will be obvious that modifications may be made in details of construction and arrangement without departing from the spirit of the invention which is not limited to such matters or otherwise than the appended claims may require.

I claim:

1. A container structure for storage battery elements comprising an open top jar, a cover arranged substantially flush with the top rim of the jar and having a peripheral flared depending flange adapted to fit closely the inner surface of the jar wall to provide a sealing channel therebetween and having a plurality of supports attached to and projecting horizontally from the top of the cover over said channel and adapted to rest on the upper surface of the jar wall, said supports having downwardly turned immovable feet adapted to engage grooves in the outer surface of the jar wall, whereby lateral displacement between the cover and the jar wall is opposed.

2. In a container structure for storage batteries, including a cover and a jar into which the cover is fitted with its top surface substantially flush with the top edge of the jar, the combination of spaced grooves provided in the outer face of the jar wall and open at its top edge, and spaced supports immovable in respect to and projecting from the cover flush with its top surface and beyond its edge and resting on the top wall of the jar so as to support said cover, said supports having feet constituting tongues aligned with the grooves.

3. In a container structure for storage batteries the combination of a jar having flat inner and outer side wall faces, a cover fitted into the jar and bounded by a downwardly and outwardly extending flange providing with the inner face of the jar wall an open channel, sealing compound in the channel, spaced grooves provided in the outer face of the jar wall and open at its edge, and spaced supports projecting from the top surface of the cover beyond its edge and spanning the channel and resting on the top of the jar wall and having tongues cooperating with said grooves, said supports providing between them openings for the introduction of the sealing compound.

4. In combination, in a storage battery, a jar, a plate structure, a cover completely detached from the plate structure, extensions provided on the top surface of said cover adapted to engage the top edge of the jar, said extensions being spaced from each other to afford clearance for the introduction of sealing compound between the cover and the inside surface of the jar wall, and downwardly disposed integral feet at the outer extremity of said extensions adapted to engage the outer surface of the adjacent jar wall to hold the edge of the cover in contact with the inner surface of the jar wall to produce a groove for receiving said sealing compound.

5. A container for a storage battery cell comprising a jar and a cover and spaced horizontally projecting supports extending from the cover to the jar wall and adapted to support said cover at the top of the jar, said supports being provided with end extensions adapted to fit grooves pro-

vided in the outside surface of the jar wall to hold the jar wall up to the cover.

6. A container structure for storage battery elements comprising a jar, a cover having a peripheral flared depending flange adapted to fit closely the inner surface of the jar wall to provide a sealing channel therebetween, and a plurality of spaced supports attached to and projecting horizontally from the top surface of the cover at the top of said jar and allowing for introduction of sealing compound to seal the cover to the inside of the top of the jar, said supports being provided with end extensions engaging the outside surface of the jar wall and adapted to hold the jar in close contact with the flange of the cover.

7. A container structure for storage battery elements comprising a jar, a cover having a peripheral flared depending flange adapted to fit closely the inner surface of the jar wall to provide a sealing channel therebetween, and a plurality of spaced supports attached to and projecting horizontally from the top surface of the cover at the top of said jar and adapted to support said cover at the top of said jar and allow for introduction of sealing compound to seal the cover to the inside of the top of the jar, said supports being provided with end extensions engaging the outside surface of the jar wall and adapted to hold the jar in close contact with the cover, said end extensions being tongues fitting grooves provided in the outside surface of the jar wall.

8. The combination in a storage battery of an open top jar, a plate structure, and a cover unattached to the plate structure and fitting into the top open end of the jar with its top surface substantially in line with the top rim of the jar wall and with its edge confronting the inner surface of the jar wall, and provided above its top surface with extensions arranged over the top edge of the jar and unattached thereto, said extensions provided with depending feet slidably fitting grooves in the outside surface of the jar and laterally holding its upper portion in contact with the edge of the cover and permitting of the removal and application of the cover by a sliding movement and without unfastening any part of the assembly.

9. In a storage battery the combination of an open top jar of rubber material having on the inside and outside of its wall substantially flat surfaces and having on the outside and near the top of its wall spaced grooves, an element supported at the bottom of the jar and having a terminal post projecting from the open end of the jar, a detachable cover of rubber material fitted into the open end of the jar and provided with an opening larger than the post through which the post passes with clearance between and further provided on its top surface with grooved pads, and metal supports attached to the top surface of the cover and arranged in the grooves in the pads and extending in line with the top surface of the cover and having depending feet arranged but not fastened in the grooves on the outside of the jar wall whereby the cover is free to be lifted from the jar without disturbing the element or any part of the assembly.

CORNELIUS AMBRUSTER.

Patent No. 2,328,535.

CERTIFICATE OF CORRECTION.

September 7, 1943.

CORNELIUS AMBRUSTER.

It is hereby certified that error appears in the printed specification of the above numbered patent requiring correction as follows: Page 1, second column, line 18, for "are" read --or--; and that the said Letters Patent should be read with this correction therein that the same may conform to the record of the case in the Patent Office.

Signed and sealed this 4th day of January, A. D. 1944.

(Seal)

Henry Van Arsdale,
Acting Commissioner of Patents.
